NARROW-FABRIC LOOM

Application filed July 28, 1927. Serial No. 208,918.

This invention relates to narrow fabric looms of the type commonly used in weaving ribbon, tape, and the like and having a plurality of shuttles reciprocated in unison. More particularly, the invention is concerned with an improved form of drive mechanism for reciprocating the shuttles and a novel shuttle construction with guide blocks therefor, these features improving the operation of the loom so that it may be run at a higher rate of speed and more quietly than looms as now constructed. In addition, by the use of these novel features, the mechanism is simplified, has greater durability, and is capable of easy adjustment when occasion arises, so that a loom constructed to embody the features of my invention produces fabric at a greater output rate and operates for longer periods without shut-downs on account of adjustment or replacement of parts.

In narrow fabric looms as now in common use, the shuttles are made of box wood and are mounted in one or more rows in wooden guides on a batten, each shuttle being guided between pairs of blocks, with one pair at each side of the reed through which the warp threads pass. A common form of drive mechanism for reciprocating the shuttles includes a rack bar on the batten for each row of shuttles, the teeth of this bar meshing with pairs of pinions which are disposed between the guide blocks, one at each side of each reed. These pinions project into the shuttle race-ways and mesh with rack teeth formed in the rear faces of the shuttles, so that as the rack bar is reciprocated, it rotates the pinions which in turn cause movement of the shuttle back and forth through the shed. The mechanism for reciprocating the rack bar includes the main drive shaft which drives another shaft through an elliptic and an eccentric gear and this second shaft is provided with crank arms to which are connected leather straps. These straps are connected to the rack bar at spaced points near one end of the bar and in the operation of the device the straps are alternately taken up and let out by the motion of the crank arms to produce a recipro-

cating motion of the group of shuttles with a period of rest at each end of the path of travel, so that sufficient time is allowed for the shed to form.

This type of shuttle drive is open to numerous objections, as for instance, frequent adjustment is required because of variation in the lengths of the straps, due to weather conditions and normal tendency to stretch. Also, as the shuttles, rack bar, pinions, and guide blocks have heretofore been commonly made of wood, as climatic conditions change, the wood frequently changes in size to an extent such that the parts get out of adjustment and bind or work loose. This causes a breakage in the teeth of the racks or pinions and necessitates replacement which is an item of considerable expense, since the loom must remain idle until repairs can be made. Sometimes the teeth of the bars and pinions become worn and break, which again results in a complete shut-down of the loom and may also involve a considerable loss in ends. Again, the variation in the lengths of the straps and the wear on the teeth of the racks and pinions makes it impossible to maintain the shuttles under exact and positive control at all times in their movements, and as the shuttles attain a considerable momentum in movement, looseness in the driving parts permits the shuttles to overrun and rebound. Also, for the same reason, the rest period in the movement of the shuttles which occurs at the end of each reciprocation is not of exact duration and as a consequence the operating parts of the loom may become damaged and frequently damage to the warp occurs.

The present invention is directed to the provision of a shuttle drive for narrow fabric looms employing a multiplicity of shuttles which overcomes the difficulties above pointed out and affords important advantages, due to its longer life, resulting from the elimination of working parts and more satisfactory performance brought about by the positive control of the shuttles at all times. The new drive mechanism permits the loom to be operated at much higher speeds than is practically possible with looms as now

constructed, and a loom which embodies the features of my invention represents a saving in installation and maintenance costs and a lower operating expense, due to the higher output rate.

The shuttle drive of the present invention may be embodied in different forms of mechanism, but preferably includes a pair of elements for driving each shuttle which may take numerous forms but may most conveniently be made as plates of semi-circular or quadrant shape mounted at intervals on a rod which extends lengthwise of the row of shuttles. Each shuttle is provided with a slot at each end and the rod with its plates is mounted in a sliding frame which has a reciprocatory movement corresponding to that to be given the shuttles. In the reciprocation of the rod, as the batten moves back and forth, the rod is rocked so as to move one or the other of the pair of plates into one of the slots in the corresponding shuttle and the shuttle is moved by this plate for a part of its passage through the shed. At the start of each shuttle movement the plate which is in effective position engages the slot at the trailing end of the shuttle, while the other plate which is placed in a different angular position on the rod, lies at one side of the threads of the shed. The plate so engaged with the shuttle establishes a driving connection between the shuttle and the rod and causes the shuttle to be moved as the rod is moved. When the leading edge of the shuttle has passed through the shed so that the channel in the shuttle is exposed, the rod is rocked so as to cause the previously operative plate to release the shuttle, while the previously inoperative plate enters the channel. The shuttle movement is now completed, with the second of the plates active and this plate remains in operative position until a part of the return movement of the shuttle is completed, when the rod is rocked to its original position.

The endwise movement of the sliding frame in which the rods, one for each row of shuttles, are mounted, may be produced by various devices but I prefer to employ a novel type of cam mechanism which includes a plate with a pair of cam grooves in which enter rollers carried by a slide bar. This sliding bar is given a reciprocatory movement by a suitable eccentric and in the course of this movement the bar is moved bodily sidewise by engagement of the rollers in the cam slots. A driving connection between the bar and the sliding frame is provided by means of a pair of pins or rods mounted on the frame and lying on either side of the bar, and the arrangement is such that as the frame carried by the batten moves back and forth, a continuous driving connection between the frame and the slide bar is maintained. At suitable intervals in the movement of the frame it is

reciprocated by the bar to cause a movement of the plate-carrying rods and the shuttles driven thereby.

Another novel feature of the invention involves the provision of a shuttle construction which is not subject to difficulties arising from variations in humidity conditions. The improved shuttle includes a wooden body portion with a fibre plate on its rear face. This plate slides in guideways formed by a pair of slotted metal plates of light construction. The fibre sliding in smooth channels in the metal plates is of indefinite life and since such fibre is not subject to warping and shrinking as moisture content of the air varies, binding or seizing of the shuttles in the guide blocks is prevented.

For a better understanding of the invention, reference may be had to the accompanying drawings, in which

Fig. 1 is a fragmentary view in front elevation showing a batten on which one form of the new shuttle drive mechanism is mounted,

Figs. 2, 3, and 4 are sectional views on the lines 2-2, 3-3, and 4-4 respectively of Fig. 1,

Fig. 5 is a diagrammatic view showing the three steps in the movement of a shuttle,

Fig. 6 is a view similar to Fig. 2, but showing a preferred form of the drive mechanism,

Figs. 7 and 8 are diagrammatic views illustrating the shuttle movement with the preferred drive mechanism,

Fig. 9 is a perspective view showing a portion of the drive mechanism illustrated in Fig. 1,

Fig. 10 is a similar view showing the preferred drive mechanism, and

Fig. 11 shows a portion of a modified form of drive mechanism, somewhat similar to that illustrated in Fig. 4.

Referring now to the drawings, the loom which is in the main of standard construction, includes a batten 10 of the usual or any standard construction, which includes an upper rail 11 and a beam 12 connected by the usual straps 13 at suitable intervals. As illustrated, this batten is provided with two rows of shuttle raceways defined by upper and lower guide blocks 14 and 15 respectively mounted on the straps in any convenient manner and preferably by an adjustable mounting which permits the upper and lower blocks to be adjusted toward and away from each other so as to increase or decrease the width of the shuttle raceway between them. The guide blocks are channeled as illustrated at 16 in Fig. 2 to provide a slot for the fibre plate 17 with which each of the wood shuttles 18 are provided. Aside from the fibre base plates, the shuttles may be of standard construction.

The blocks 14 and 15 are of light metal construction, such as iron castings, and are made single and double, as illustrated. The double

block 14 includes a pair of individual blocks 19 which form part of the raceway for a single shuttle and are disposed at either side of a reed which occupies a space designated 20. The portions 19 are connected by an extension 5 piece 21 which passes across the space occupied by the reed but is offset to a sufficient extent beyond the portions 19 as to provide suitable clearance for the warp threads passing through the reed. Associated with each 10 double block 14 are the single blocks 15 mounted on the straps 13 one on each side of the space 20 for a reed. With this arrangement the slots 16 in the faces of the portions 15 of the double block may be accurately 15 formed and in a plane and the single blocks 15, by reason of their adjustable mountings, may then be properly aligned with the portions 19 so that a raceway is formed between 20 the blocks in which the shuttle may move without binding. This combination of metal shuttle guide blocks and shuttles with fibre plate members which move in the raceways formed by their blocks eliminates difficulties 25 heretofore of great importance arising from warping or shrinking of the wood blocks and shuttles previously used, and at the same time the weight of the reciprocating shuttles is not added to, since the shuttles with the light 30 fibre plates are not substantially different in weight from the all-wood shuttles now in use.

Each shuttle is provided with a pair of channels or grooves 22, one at each end of the shuttle, these channels being formed either 35 in the upper or lower face of the shuttle, depending on whether the shuttle is to be placed in the upper or lower row in the batten. The shuttles are symmetrical in form so that they may be used in either row simply by 40 turning one face or the other uppermost. In order to reciprocate the shuttles, I may employ different forms of my invention both operating on the same principle. In one of these forms the batten is provided with 45 brackets 23 secured to the straps 13 and extending forwardly over the uppermost row of shuttles. These brackets are provided with blocks 24 which are undercut so as to receive a slide bar 25 having depending 50 brackets 26 terminating in bosses 27 in which is mounted a rod 28. At suitable intervals this rod is provided with collars 29, one on 55 each side of a boss 27, so that the rod, while free to rock in the boss, is incapable of end- wise movement with reference to the boss. At one end of the batten beam 12 the rod 28 passes through a bracket 30 on a plate 31, this 60 plate having a depending bracket 32 on which is mounted a shaft 33 carrying a bevel gear 34 meshing with a smaller bevel gear 35 on the end of the rod 28. At its rear end the shaft 33 carries a forked arm 36 fast thereon and on a stud 37 in the bracket 23 is mounted a roller 38 in a position to be received between the 65 spaced ends of the arm 36.

The arrangement of the parts above described is such that as the slide 25 is moved in one direction in the batten, the forked arm 36 straddling the roll 38 on stud 37 is rocked through 90° and through the shaft 33 and 70 gears causes the rod 28 to rock through 180°. At spaced intervals on the rod 28 are plates 39 of quadrant form arranged in pairs and spaced apart a distance equal to the distance between a pair of grooves in the opposite 75 ends of the shuttle. These quadrants are angularly offset 90° on the rod 28 and the arrangement is such that at the start of movement to the right, as illustrated in Fig. 1, the quadrant 39^a at the trailing end of each 80 shuttle is in operative position, that is, the rod 28 has an angular position in which this quadrant enters the channel at the rear end of a shuttle 18. Upon movement of the slide 25 toward the right, the rod 28 is carried along with it, and the quadrants which are in operative position establish driving connections between the shuttles in the row and the rod 28, while the quadrants 39^b, which are not in engagement with shuttles, occupy 85 a position in which they will not interfere with the shed as the rod moves. When the slide 25 and the shuttles driven by it have moved to an extent such that the leading end of each shuttle has passed through the shed 90 and the channel in this end of each shuttle is exposed, the rod 28 is rocked by engagement of the forked arm 36 with the roller 38 mounted on the stationary stud 37 on the batten frame, and upon such rocking the 95 quadrants 39^b move down to enter the channels in the leading edge of the shuttles, while the quadrants 39^a are raised out of their respective channels and take a position so that they will clear the sheds passing through 100 the reeds in the spaces 20. The rod 28 occupies the new angular position until the completion of the shuttle movement, and until the return movement has progressed to an extent such that the leading end of each 105 shuttle has again passed through its shed, whereupon the rod is rocked to its original position and quadrants 39^a complete the shuttle movement, while quadrants 39^b are raised to the inoperative position illustrated 110 in Fig. 1.

The shuttles of the upper row are operated by quadrants placed on a rod which lies above the row of shuttles, while the shuttles of the lower row are operated by similar 115 mechanism, but the rod and quadrants for these shuttles are placed beneath them. Other minor changes in construction are necessary in this arrangement. The rock rod 28^a of the lower group is mounted in brackets 120 26^a secured to a slide 25^a which is secured at one end to a member 31^a disposed at one end of the batten. This member 31^a has a pair of spaced channels 43 in its lower face in 125 which are received the upstanding legs 44 130

of a U-shaped bracket 45 secured to the batten beam. The member 31^a is provided with a bracket 30^a through which the rod 28^a passes, and the rod is rocked by gears and a forked arm and pin similar to those previously described in connection with the upper mechanism. The two members 31 and 31^a are connected by a cross bar 46 and between these members are mounted rods 47 carrying cylindrical sleeves 48. Between these sleeves passes a slide bar 49 which is given a reciprocatory movement equal to the throw of a single shuttle and as the bar 49 is reciprocated, all of the shuttles are moved back and forth across the sheds by the rock rods 28 and the quadrants. In Fig. 1, the parts are shown in the positions they occupy at the start of their movement to the right, as indicated by the arrow.

The operation of the plates is more clearly illustrated in Fig. 5, in which the view *a* shows a single shuttle of the lower row at the beginning of its movement to the right. Here the quadrant 39^a is engaged in the channel in the shuttle at the trailing end thereof, while the quadrant 39^b is in a downward position. When the shuttle 18 is in the position illustrated in Fig. 5^b, the leading end of the shuttle has passed through the shed 30 and its channel is exposed. As soon as the shuttle has reached this position, the rod 28^a is rocked to bring the quadrant 39^b into operative position and in engagement with the channel in the shuttle, while the quadrant 39^a has moved clear of its channel and down so that it will clear the shed without interference. Upon completion of the rocking of the rod 28^a, the quadrants are in the position illustrated in Fig. 5^c, where the quadrant 39^b is in full operating position and the quadrant 39^a has been carried to a point where it will not interfere with the shed through which the shuttle is passing.

In the construction described, each row of shuttles is provided with a member extending the length of the row and carrying means for establishing an operative connection between the shuttles of that row and the member, but instead of using separate drive rods and plates for each row of shuttles, the rows of shuttles may be placed close together and the shuttles of both rows driven by means of a single rod, in which event the construction illustrated in Fig. 6 will be employed. This construction I prefer on account of its simplicity, although for certain widths of fabric, the construction illustrated in Fig. 1 may be used to better advantage.

In this preferred construction there is provided a slide bar 50 mounted in any convenient manner, as, for example, in a groove formed between adjacent shuttle guide blocks of the upper and lower groups. This slide bar is arranged for reciprocating movement and carries brackets 51 in which the

rock rod 52 is mounted. This rock rod is provided with semi-circular plates 53 spaced at suitable intervals. The shuttles of the upper row, as illustrated in Fig. 7, are provided with channels 54 at opposite ends and in their lower faces, while the shuttles of the lower row have similar channels but in their upper faces. The channel in the left-hand end of a shuttle of the upper row is opposite the channel in the right-hand end of a shuttle of the lower row and alternate plates 53 have an angular spacing of 180° on the rock rod. The spacing of the shuttles is such that when the bar is rocked to one position, one plate is in operative connection with the left-hand end of a shuttle of the upper row, while the next plate is in operative connection with the left-hand end of a shuttle of the lower row. At the beginning of the shuttle movement, the rod is rocked so that the plates establish an operative connection between the rod and the trailing ends of the shuttles in the two rows, and this relation of the parts continues until each shuttle has passed through the shed and its forward end is exposed. Thereupon the rock rod is moved to a position in which each plate releases the shuttle with which it was first engaged and engages a shuttle of the opposite row. The movement of the rock rod and the position of the plates on it is such that when a plate is engaged with a shuttle of one row, it will clear the shed through which its associated shuttle of the other row passes, and at the beginning of each shuttle movement each shuttle is moved by a plate which engages its trailing end and the shuttle movement is completed by a plate which engages its leading end.

In Fig. 7 the plate 53^a is in engagement with the trailing end of the shuttle 18^a and in a position in which it will clear the shed in the space 57, while the plate 53^b is in engagement with the trailing end of the shuttle 18^b and in a position in which it will clear the shed in the space 60. When the shuttles have moved to the position illustrated in Fig. 8, the plate 53^a is moved by rocking of the rod 52 to a position in which it engages the leading end of the shuttle 18^a, and is completely free of the shuttle 18^a. The plate 53^b has been moved down to engage the leading end of the shuttle 18^a and has thus freed the shuttle 18^b. The shuttle 56 is now moved to the end of its path of travel by the plate 53^b and the plate 53^a passes over the shed in the space 60. On the return movement the cycle of operations is reversed.

The mechanism for moving the slides 25 and 25^a back and forth includes the bar 49 which passes between upright bars 47 extending between the members 31 and 31^a secured to the ends of the slides. The bar 49 is provided with cam rollers 63 at its opposite ends which run in slots 64 in spaced plates 65 and 66 secured to the end members of the

loom frame. These plates are suitably placed so as not to interfere with the swinging movement of the batten and the bar 49 is of a length sufficient to permit a free movement 5 of the batten without affecting the operative connection between the bar and the rods 47. The plate 65 has an extension 67 on which a lever 68 is pivotally mounted on a stud 69. The free end of this lever is connected by a 10 link 70 to the end of the rod 49 and between its ends the lever is connected to a link 71, the other end of which is mounted on an eccentric pin 72 on a gear 73, meshing with a gear 74 on the vertical shaft 75. These looms 15 are normally provided with a jacquard pattern mechanism driven by a vertical shaft, and this shaft may be that designated 75 in the drawings. With this arrangement of the parts, upon rotation of the gear 73 the lever 20 68 is rocked about its pin 69 and its movement is transmitted through the link 70 to the bar 49. The bar reciprocates back and forth in the same direction as the batten swings and in the middle of its reciprocating movement 25 the bar 49 is moved bodily sidewise by reason of the engagement of the rollers 63 in the cam slots 64. In this bodily sidewise movement the bar 49 causes a movement of the slides 25 and 25^a connected together and 30 provided with the rods 47 extending between them. Preferably these rods are mounted in bracket bearings 76 which are secured to the members 31 and 31^a by a slot and pin connection, as illustrated at 77 in Fig. 4, and 35 this permits the rods 47 to be adjusted in position with reference to the bar 49 so that the desired clearance may be secured and the position of the rods may be adjusted with reference to one another as wear occurs. 40 With this arrangement, a positive driving connection is insured between the bar 49 and the slides by which the shuttles are driven, and the shape of the cam slots determines the extent of the throw of the shuttles.

45 It will be noticed that the cam slots are provided with a dwell at each end representing a period of rest in the shuttle movement at each end of the path of travel of the shuttle and in between these dwells the slots are disposed at an angle to produce a shuttle movement 50 at the desired speed. If the shuttle throw is to be varied, then plates with different types of slots will be substituted for those designated 65 and 66, and some changes in the 55 linkage may also be necessary.

60 In some installations it may be desirable to have the operating mechanism for the slide bars mounted on the floor or in some other position, instead of at the end of the loom frame, and in such a situation the modified driving mechanism illustrated in Fig. 11 will be employed. Here the plates 65 and 66 are mounted on the floor and the rod 49 is connected by means of a clamp 78 to a pivoted 65 lever 79 extending through a clamp 80 pivot-

ally mounted on a rod 81 which is supported in an upright member 82. The free end of the lever 79 is slotted, as indicated at 83, and a pin 84 on a cross member extending between the slides 25 and 25^a lies in the slot 83. The 70 slotted end of the lever is connected to the remainder by a joint 85 and the clamp 80 permits endwise movement of the lever 79 through it. The rod 81 is adjustably mounted in the upright 82 so that the clamp 80 75 which serves as the pivot point of the lever, may be placed at different positions. With this arrangement, as the rod 49 is moved sidewise bodily it swings the rod 79 about the pivot point of the clamp 80 as a center 80 85 and the free end of the rod causes the reciprocating movement of the slides. The joint 85 permits the connection to be maintained between the lever 79 and the slides during the swinging movement of the batten.

It will be seen that in the new loom the shuttles in one or more rows are reciprocated as a group by a single element carrying means by which an operative connection between the element and the shuttles is established. These 90 means are arranged to operate to establish a connection between the trailing end of each shuttle and the reciprocating member at the start of each shuttle movement in each direction, and then as soon as each shuttle has 95 passed partly through its shed, the original connection is broken and a new connection is established between the member and the leading end of each shuttle. The quadrants or semi-circular plates used for establishing the 100 connection are so disposed on the rock rod that in the rocking of the latter at one instant in the shuttle travel, the shuttle is engaged both at its leading and trailing ends, but immediately thereafter one or the other 105 of the elements on the rock rod is released from the shuttle. The consequence is that throughout its movement and while it is at rest, the shuttle is always operatively connected with the rock rod, but not by the same 110 element on that rod. Accordingly, each shuttle is under positive control at all times and overrunning, with the consequent rebound and variation in the rest period of each shuttle, is avoided. The quadrant or semi-circular plates on the rock rod are preferably made 115 of light metal and as the shuttle guide blocks are likewise of metal and the parts of the shuttle which lie in these raceways are of fibre, difficulties such as occur with wooden 120 driving and guiding devices are overcome. Also, the durability of the parts is greatly increased and as the parts move freely and are under perfect control, a much higher 125 loom speed is obtainable. The new guide blocks are constructed in such a way that perfect alignment is readily secured and adjustment of the parts is simple. The original setting up of the mechanism is extremely simple because all that is necessary is to place all 130

the shuttles at one end of their path of travel, set the slides in the proper relation, and then adjust the plates on the rods in the proper positions. Each plate has a boss through which the rod extends and the plate may be secured to the rod in proper angular position by means of a set screw. Once the plates are properly placed, no change is necessary in their setting, and as all the parts are in exposed position where they are readily accessible, adjustment or replacement does not necessitate shutting down the loom for any considerable length of time.

The new cam mechanism for driving the slides is of simple construction and positive in action and it avoids the use of leather straps and of elliptic and eccentric gears such as have heretofore been necessary and are a constant source of annoyance and difficulty.

20 I claim:

1. In a loom, the combination of a batten, a shuttle mounted for reciprocation thereon, said shuttle having spaced recesses formed therein, a member movable endwise and parallel to the direction of shuttle movement, a pair of spaced plates carried by the member and adapted to enter the shuttle recesses to cause movement of the shuttle, means for reciprocating the member, and means for 25 rocking the member to cause the plates to engage and disengage the shuttle alternately, said plates in the rocking of the member entering the recesses in their respective shuttles at opposite ends of said recesses.

35 2. In a loom, the combination of a batten, a plurality of shuttles mounted on the batten in a row and reciprocable lengthwise of the row, a rod extending lengthwise of the row and reciprocable parallel thereto, a plurality of pairs of plates carried on the rod, one pair for each shuttle, these plates being adapted to engage the shuttle alternately from opposite directions and establish an operative connection between the shuttle and the rod, similar 40 plates of each pair being placed in similar angular positions along the rod, while the other plates of each pair are in similar positions but spaced angularly from the first plates, means for reciprocating the rod, and means for rocking the rod to cause the plates carried thereby alternately to engage the shuttles.

45 3. In a loom, the combination of a batten, a shuttle movably mounted thereon, a rod movable endwise and disposed spaced from the shuttle between the planes of its base and top, plates carried by the rod and adapted to engage the shuttle and establish an operative connection between the shuttle and the rod, means for moving the rod endwise, and means 50 for causing the rod to rock to move the plates into and out of engagement with the shuttles successively, the rocking means including a stationary member and a swinging arm connected to and movable with the rod and rocked

by engagement with the stationary member during the reciprocation of the rod.

4. In a loom, the combination of a batten, a shuttle movably mounted thereon, a rod movable endwise and parallel to the path of travel of the shuttle, a pair of plates carried by the rod and adapted to be engaged with opposite ends of the shuttle to establish an operative connection between it and the rod, and means for causing rocking movement of the rod at selected intervals in its path of travel endwise to cause the plates carried by it to engage and disengage the shuttle alternately, the said means including a shaft movable with the rod, an arm on the shaft, gearing connecting the shaft to the rod, and a stationary member engaged by the arm and causing rocking movement of the arm and shaft during the reciprocation of the rod.

5. In a loom, the combination of a batten, a multiplicity of shuttles disposed on the batten in two parallel rows and reciprocable lengthwise of the rows, a member disposed adjacent the rows of shuttles and carrying means adapted to engage alternately with one shuttle in each row, means for reciprocating the member, and means for giving the member another movement to cause the means carried thereby to engage a shuttle in each row alternately and produce a movement thereof as the element is moved.

6. In a loom, the combination of a batten, a multiplicity of shuttles mounted thereon in two parallel rows and movable lengthwise of the rows, a rod disposed between the rows and movable lengthwise of the rows, plates carried by the rod, each plate being adapted to engage a shuttle in each row, means for moving the rod lengthwise, and means for rocking the rod to cause each plate to engage a shuttle in each row alternately to produce movement thereof as the rod is moved.

7. In a loom, the combination of a batten, a shuttle mounted movably thereon, this shuttle having recesses at its opposite ends, a rod movable lengthwise and arranged to rock a pair of plates carried by the rod in spaced relation and adapted upon rocking of the rod to be brought alternately into engagement with spaced recesses in the shuttle, means for reciprocating the rod, and means for rocking the rod to cause the plates to enter their respective recesses alternately and from opposite directions.

8. In a loom, the combination of a batten, a multiplicity of shuttles arranged on the batten in two parallel rows, these shuttles being movable lengthwise of the rows and each shuttle having recesses formed in its opposite ends, the shuttles being placed in the rows with the recessed faces of the shuttles in the two rows toward each other, a rod disposed between the rows of shuttles, plates of semi-circular form disposed at intervals on the rod, each plate being adapted to enter a re-

cess in a shuttle in each row, means for reciprocating the rod lengthwise, and means for rocking the rod to cause the semi-circular plates alternately to engage in the recesses of shuttles in the two rows.

5. 9. In a loom, the combination of a batten, a slide mounted in the batten, means connected to the slide for reciprocating it lengthwise of the batten, a shuttle mounted in the batten and movable lengthwise thereof and parallel to the slide, a rod carried by the slide and free to rock with relation thereto, means carried by the rod for engaging the shuttle at opposite ends alternately, and means for rocking the rod to render the said connecting means operative, the said rocking means including a shaft mounted on the slide, an arm connected to the shaft, a stationary pin engaging and rocking the arm as the slide reciprocates, and gearing between the shaft and the rod.

10. In a loom, the combination of a pair of shuttles movable in parallel raceways and means disposed adjacent the shuttles adapted to engage and move the shuttles, said means being movable in the direction of travel of the shuttles and including elements engageable with the two shuttles alternately, each shuttle being continuously engaged with one or another of said elements.

11. In a loom, the combination of a plurality of shuttles mounted in rows, and means for operating the shuttles including elements connectible to a shuttle in each row alternately and movable in the direction of travel of the shuttles, each shuttle being continuously connected to an element.

12. In a loom, the combination of a pair of shuttles in spaced, parallel raceways, and elements between the shuttles operable to engage the shuttles alternately and move them, said elements being movable in the direction of shuttle movement and each shuttle being continuously engaged with an element.

13. In a loom, the combination of a plurality of movable shuttles in spaced rows, and means operable to engage the shuttles of the two rows and move them, said means including elements between rows and movable parallel thereto and also movable to engage a shuttle of each row in alternation, each shuttle being continuously engaged with an element.

14. In a loom, the combination of a plurality of shuttles movably mounted in aligned raceways in spaced rows, and means disposed adjacent the rows for moving the shuttles including a plurality of elements each of which is adapted to be engaged with a shuttle in each row alternately and a member carrying said elements and movable lengthwise of the rows.

15. In a loom, the combination of a plurality of shuttles in aligned raceways in spaced rows, a member extending lengthwise of the rows of shuttles and lying between the front and rear edges thereof, and means

on said member for directly engaging the shuttles and moving them.

16. In a loom, the combination of a shuttle mounted for endwise movement, a member extending parallel to the direction of said movement and lying between the front and rear edge of the shuttle, and means rigidly mounted on the member and movable with the member in either of two directions to engage the shuttle to connect it to the member.

17. In a loom, the combination of a plurality of shuttles in spaced rows and mounted for movement lengthwise of the rows, a member lying between the rows and movable in the direction of shuttle movement, this member lying between the front and rear edges of the shuttles, and means on the member movable in either of two directions to effect a connection between the shuttles and the member.

18. In a loom, the combination of a plurality of shuttles in spaced rows and mounted for movement lengthwise of the rows, a member between the rows, means on the member for connecting the member and the shuttles, means for reciprocating the member and means for rocking it to render said means effective to connect shuttles of the two rows alternately to the member.

19. In a loom, the combination of a shuttle having a slot in each end, these slots being open at both ends, a member lying adjacent the shuttle between its front and rear edges, and spaced means on the member adapted on rocking thereof to enter the slots of the shuttle from either end in alternation, whereby the oscillation of the member causes first one end of the shuttle and then the other to be connected to the member.

20. In a loom, a plurality of raceways in upper and lower rows defined by spaced guide blocks, shuttles disposed in the raceways, a bar movable in a channel defined by adjacent guide blocks of the two raceways, and means carried by the bar for alternately connecting the shuttles in the upper and lower raceways thereto.

21. In a loom, a shuttle mounted for endwise movement, this shuttle having open-ended slots in each end extending at an angle to the direction of shuttle movement, a rod extending parallel to the direction of shuttle movement and lying between the front and rear edge of the shuttle, and a pair of plates on the rod in registry with the slots and adapted to be alternately engaged therein through either end of said slots by rocking of said rod in either direction.

22. In a loom, the combination of a batten, spaced rows of shuttles on the batten, a rod between the rows movable lengthwise thereof, plates carried by the rod, each plate being adapted to engage a pair of shuttles one in each row, means for reciprocating the rod, and means for rocking it during its recipro-

cation to cause the plates to engage the shuttles of the rows in alternation.

23. In a loom, the combination of a batten, spaced rows of shuttles thereon, a rod adjacent the rows movable lengthwise thereof,

5 semi-circular plates carried by the rod, each plate being adapted to enter a slot in each of two shuttles, one in each row, means for reciprocating the rod, and means for rocking it during its reciprocation to cause the plates

10 to enter the slots in shuttles of the two rows alternately.

24. In a loom, the combination of a batten, spaced rows of shuttles thereon, each shuttle

15 having a slot in each end, a rod adjacent the shuttles movable lengthwise of the rows, plates disposed in pairs on the rod, the plates of each pair being angularly offset and each plate being adapted to enter a slot in a shuttle

20 in each row, means for reciprocating the rod, and means for rocking it to cause each plate to enter a slot in a shuttle in each row alternately.

25. In a loom, the combination of a batten, spaced rows of similar shuttles thereon, each

25 shuttle having a slot in each end, and the shuttles in the rows being staggered with the slots in the forward ends of the shuttles of one row lying in registry with those in the rear ends

30 of the shuttles in the other row, a rod extending adjacent the rows, plates on the rod spaced a distance corresponding to the spacing between a pair of slots in a shuttle, alternate plates being angularly offset where-

35 by when the odd plates on the rod engage the slots in the shuttles in one row the even plates engage the slots in the shuttles in the same row, means for reciprocating the rod and means for rocking the rod to reverse the engagement of the plates and shuttles.

26. In a loom, the combination of a batten, a plurality of shuttles mounted thereon in spaced rows and movable lengthwise of the rows, the shuttles of one row lying opposite

45 spaces between shuttles in the other row, a slot in each end of each shuttle, the shuttles in each row being spaced a distance such that the interval between slots in adjacent ends of successive shuttles is equal to the distance

50 between the slots in the shuttle in the other row opposite the space between said successive shuttles, and driving means adapted to enter said slots to drive the shuttles.

27. In a loom, a plurality of shuttles

55 mounted in a row, each shuttle having a recess in each end adapted to be entered by shuttle driving means, and the shuttles being so mounted that the distance between adjacent slots in any pair of shuttles in the row is

60 equal to the distance between the slots in opposite ends of any shuttle in the row.

28. In a loom, the combination of a batten, a plurality of spaced reeds thereon, raceways for shuttles disposed in alignment between

65 the reeds, a shuttle movable in the raceways

past each reed, each of the raceways having a length sufficient to receive the shuttle, and each shuttle having a recess at each end, adapted to be engaged by shuttle driving means, the shuttles being so disposed in the raceways that the distance between a pair of slots in the opposed ends of a pair of adjacent shuttles is equal to the distance between a pair of slots in a single shuttle.

29. In a loom, the combination of a batten, 75 a plurality of spaced reeds thereon, raceways for shuttles disposed in alignment between

70 the reeds, a shuttle movable in the raceways past each reed, each of the raceways having a length sufficient to receive the shuttle, and

80 each shuttle having a recess at each end, the shuttles being so disposed in the raceways that the distance between a pair of slots in the opposed ends of a pair of adjacent shuttles is equal to the distance between a pair of slots in a single shuttle, a member extending

85 lengthwise of the row and means on the member adapted to enter the slots, said means being evenly spaced on the member a distance

90 equal to the spacing between a pair of slots in a shuttle.

30. In a loom, the combination of a shuttle

95 mounted for endwise movement, a member extending parallel to the direction of said

movement, a pair of elements mounted fast

100 on said member, one near each end of the shuttle and spaced angularly with respect

105 to said member, said elements being alternately engageable with the shuttle upon

110 rocking of the member and upon said engagement connecting the shuttle and member,

115 means for reciprocating the member, and means effective during the reciprocation

120 of the member for rocking it through an angle sufficient to move one element out of engagement with the shuttle and the other element into engagement therewith.

31. In a loom, the combination of a shuttle

125 mounted for endwise movement, a pair of elements disposed one near each end of the shuttle, said elements being movable parallel to

130 the direction of shuttle movement and also capable of oscillation about the same axis which extends parallel to the direction of

135 shuttle movement, said elements being angularly displaced with reference to said axis,

140 means for reciprocating the elements in a direction parallel to the direction of shuttle movement, and means for rocking the elements simultaneously through an angle of

145 substantially 180° during said reciprocation, said elements being alternately engaged with

150 and disengaged from said shuttle by said

155 rocking movement.

32. In a loom, the combination of a shuttle

160 mounted for endwise movement, a member extending parallel to the direction of said

165 movement, a pair of elements of semi-circular

170 form mounted fast on said member, one near each end of the shuttle, said elements being

spaced angularly with respect to said member and being alternately engageable with the shuttle upon rocking of the member for connecting the shuttle and member, means for reciprocating the member, and means for rocking the elements through an angle of substantially 180° during its reciprocation.

5 In testimony whereof I affix my signature.
HERMAN BAADER.
